(57) **CLAIM**

The ornamental design for a power tool, as shown and described.

DESCRIPTION

FIG. 1 is a left side perspective view showing our design for a power tool;

FIG. 2 is a top view thereof;

FIG. 3 is a left side view thereof;

FIG. 4 is a rear view thereof;

FIG. 5 is a front view thereof;

FIG. 6 is a bottom view thereof; and,

FIG. 7 is a rear perspective view thereof.

The broken line showing of some features of the power tool is for illustrative purposes only and forms no part of the claimed design.
